UNITED STATES PATENT OFFICE.

JOSÉ GALLEGOS, OF ANTIGUA, GUATEMALA.

DISTILLING APPARATUS.

SPECIFICATION forming part of Letters Patent No. 591,340, dated October 5, 1897.

Application filed April 20, 1897. Serial No. 632,958. (No model.)

To all whom it may concern:

Be it known that I, JOSÉ GALLEGOS, of Antigua, Guatemala, have invented new and useful Improvements in Distilling Apparatus, of which the following is a full, clear, and exact description.

My invention relates to distilling apparatus, and has for its object to provide means whereby the pressure within the apparatus will be kept practically constant, so as to prevent any excessive pressure that might burst the apparatus. Another object is to prevent the loss of vapors of the substance under distillation.

To this end my invention consists of the novel construction hereinafter described and claimed.

Reference is to be had to the accompanying drawing, which is a diagrammatic elevation of a distilling apparatus constructed according to my invention.

A is the furnace, carrying the still B or a retort or other equivalent. C is the grate. From the still B a tube D leads to the coil E, arranged within the cooler F. The lower end or outlet of the coil E is connected to the receptacle G, in which the products of distillation are adapted to collect. The receptacle G communicates by a tube H with bellows I, whose bottom I' is stationary. The top I² of the bellows is capable of moving up and down, and the bellows is counterbalanced or partly counterbalanced by means of a weight K, attached to one end of a flexible connection, such as a wire or chain L, the other end whereof is secured to the top I² of the bellows I. Said flexible connection passes over a pulley M, which is journaled in stationary bearings.

The tube H is connected to a suction-tube N, which may be connected directly to the interior of the bellows I, if desired.

Cocks or valves O are provided wherever they may be required or desirable.

P is the outlet-cock for withdrawing the condensed products of distillation from the receptacle G.

The suction-tube N is connected to the suction-port of an air-pump (not shown) or to any air-exhausting device.

50 The operation of the apparatus is as follows: The cocks O being all open the products of distillation pass through the tubes D and E,

the condensed substance collecting in the receptacle G. During the suction stroke of the air-pump a partial vacuum is produced in the apparatus, and the atmospheric pressure causes the bellows I to collapse. When, however, suction is discontinued, the pressure within the apparatus will cause the bellows to expand, the counterbalancing-weight K enabling the bellows to respond to even slight variations of pressure. The result is that the internal pressure will remain practically constant, so that the strain on the parts of the apparatus will be always the same and all danger of bursting will be obviated. The expansion-chamber formed by the bellows I thus constitutes a safety device. It is, however, materially different from a safety-valve in that it does not allow any of the vapors to escape, but as the said chamber is closed the loss of vapors is prevented.

It will be understood that only the condensation product collects in the receptacle G, while substances that remain gaseous or solid are withdrawn by the action of the air-pump or other exhaustor.

The wire or chain L, in conjunction with the pulley M, also acts as a guide for obtaining a true vertical movement of the bellows.

While the apparatus is more sensitive and reliable when provided with a counter-weight, such as K, and a guide, such as L M, such counterweight and guide are not absolutely indispensable.

Instead of the bellows I might employ a stationary cylinder, preferably open at its upper end and containing a piston which might be connected to the wire L in the same manner as shown for the top I² of the bellows. This modification is so simple that I have not deemed it necessary to illustrate it. It obviously is a functional equivalent of the bellows.

My improved apparatus is particularly intended for use in the distillation of alcohol.

Having thus described my invention, I claim as new and desire to secure by Letters Patent—

1. The combination of the still, and the expansion-chamber having a movable wall so that its volume can vary according to the pressure within the apparatus and the cooler or condenser located between the still and

the expansion-chamber, substantially as described.

2. The combination of the still, the cooler or condenser, the expansion-chamber having a movable wall so that its volume can vary according to the pressure within the apparatus, and a counterbalance connected to said movable wall, as and for the purpose set forth.

10 3. The combination of the still, the cooler or condenser, the bellows connected to said condenser, and having a stationary wall, and a movable wall opposing the stationary wall, a flexible connection, one end whereof is secured to said movable wall, and a counterweight secured to the other end of said connection, substantially as described.

4. The combination of the still, the cooler or condenser, the expansion-chamber connected to the condenser and having a movable wall, a flexible connection, one end

whereof is secured to said movable wall, and a counterweight secured to the other end of said connection and tending to draw the movable wall away from the stationary part of the expansion-chamber, substantially as described.

5. The combination of the still, the cooler or condenser, the expansion-chamber connected to the condenser and having a stationary bottom and a movable top wall, a flexible connection extending upwardly from said movable top, a pulley or guide over which passes said connection, and a counterweight secured to the free end of the said connection and arranged to pull said movable wall upward, substantially as described.

JOSÉ GALLEGOS.
